UNITED STATES PATENT OFFICE.

HAROLD G. WARE, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed June 9, 1927. Serial No. 197,602.

My invention relates to improvements in rail anchors.

One of the objects of the invention is to provide an improved rail anchor which may 5 be formed from a metal blank cut from a relatively narrow strip of flat metal stock and in which the configuration of the blank is such as to simplify the shearing operation and economize in the amount of metal used. 10 Another object is to provide an improved one-piece rail anchor which may be made from a relatively thin metal strip and which is so formed as to provide a substantially rigid jaw portion the effective width of 15 which is greater than the thickness of the blank and so as to provide a jaw portion of sufficient width to prevent any actual rocking of the jaws about a horizontal axis when the lower portion of the anchor is pressed 20 against a cross tie, and thereby prevent the excessive strains on the jaws incident to such rocking movement.

A further object is to provide a one-piece anchor of the general type shown in the accompanying drawings which will be less expensive to manufacture than devices of this type heretofore used and which will have the improved constructions hereinafter described and claimed.

The invention is illustrated in several specific embodiments in the accompanying drawings, wherein

Fig. 1 is a side view of a rail anchor constructed in accordance with my invention, applied to the base flange of a railroad rail in a position to bear against one of the adjacent cross ties.

Fig. 2 is a plan view of the construction shown in Fig. 1.

Fig. 3 is a sectional view taken on line 3—3 of Fig. 1.

Fig. 4 is a flat view of the blank from which the embodiment just described is formed, showing in dotted lines the point where the blank is to be bent.

Fig. 5 is a view in perspective showing in full lines a partially formed anchor and illustrating in dotted lines the jaw end of the anchor after it is bent to its completed form.

Fig. 6 is a view in perspective of a modified construction showing the rail-engaging jaws spaced apart so as to provide for some resiliency in the bar portion of the anchor.

Fig. 7 is a view similar to Fig. 3, but illus-

trating the modified construction of Fig. 6. 55

Fig. 8 is a view in perspective of another modified embodiment.

Fig. 9 is a sectional view similar to Fig. 3 illustrating the modification of Fig. 8 in its applied position on the base flange of the 60 rail.

Fig. 10 is a side view of a further modified construction, in which short shoulder portions are provided for engaging opposite vertical edges of the rail base. 65

Fig. 11 is a sectional view taken on line 11—11 of Fig. 10 looking in the direction indicated by the arrow.

Fig. 12 is a view in perspective of the modified anchor device illustrated in Figs. 70 10 and 11, and

Fig. 13 is a view similar to Fig. 3 but showing greater clearance between the vertical surfaces of the cross bar and the jaw portion of the anchor. 75

The embodiment of my invention shown in Figs. 1 to 3 inclusive consists of a rail base embracing member having a relatively thin body portion 10 positioned edgewise relative to the bottom surface of the rail. One 80 end of the body is formed with a relatively rigid jaw portion consisting of spaced upper jaws 11—11^a and lower jaws 12—12^a. The jaws are spaced with relation to each other, longitudinally of the rail, so as to provide 85 rail engaging surfaces of sufficient width to prevent any actual rocking of the jaw end of the anchor when the lower portion 13 of the jaw end is pressed against the cross tie 14. While the width of the bearing surface of 90 the jaw end of the anchor is sufficient to prevent any actual rocking of the jaws about a horizontal axis and thereby prevent excessive strains on the jaws incident to such actual rocking, the width is preferably narrow 95 enough to effect an increased gripping force, by shackle engagement on the top and bottom surface of the rail base, when the lower portion of the anchor is pressed against the cross tie. The body portion 10 preferably extends downwardly at an angle from the bottom surface of the rail base, so as to provide a tie-abutting surface which will bear against the cross tie at a substantial distance below the bottom surface of the rail base. 105

The other end of the body is recessed to provide a small shoulder 17 adapted to snap over the opposite edge of the rail base to lock

the anchor in its applied position when the anchor is driven transversely of the rail into its operative gripping position.

The anchor above described is made preferably from a narrow strip of metal cut from a rolled metal strip of the desired width and thickness. The spaced jaws are formed by providing the margin 18 of the blank with adjacent recesses 19, 20 and by so bending the end 21 of the blank as to bring the said recesses into substantial alignment with each other. The recesses 19 and 20 are formed preferably by punching operations so that the walls of the recesses will taper toward one side of the blank. When the jaw end 21 of the blank is bent to its finished position, the tapered walls of the recesses provide sharp outer edges which are crushed down by contact with the rail and are thereby made to conform with the rail so as to provide a firm frictional grip. With this construction the space between the jaws may be made smaller than the thickness of the rail base, the compression of the edges of the jaws being relied upon to produce the desired fit. This feature of the invention also permits an anchor of one standard size to be applied to rails having base flanges of different thickness. The blank is bent along line 22 until the jaw end of the blank engages or substantially engages the flat side face of the body portion as shown in full lines in Fig. 5. The bend is made in this manner, preferably, to provide rigidity between the body portion and the jaw end of the anchor and at the same time provide sufficient clearance between adjacent surfaces thereof to facilitate the tempering of the metal. The line 22, along which the blank is bent, may be at any suitable angle relative to the longitudinal edges of the blank. In the embodiment above described, the line 22 extends across the blank at an angle greater than 45° with respect to the edges of the blank so that when the jaw end of the anchor is disposed perpendicular to the bottom surface of the rail base, the body portion 10 of the anchor will extend at an angle to the bottom surface of the rail base. By making the bend 23 in the above manner, the locking shoulder 17 and the bottom bearing surface 24 at the other end of the anchor may be formed by shearing the angular recess 25 in the opposite edge of the blank.

The end portion 21 is bent along the line 26 of Fig. 4 to the position indicated in dotted lines in Fig. 5, to form the U-shaped jaw end of the anchor and to bring the recesses 19 and 20 into alignment, and to position the jaw members in their properly spaced relationship to each other. It will be seen from an inspection of the drawing, that the spaced jaw portions are disposed on opposite side faces of the body portion.

This arrangement equalizes the distance from the shoulder 17 to each of the jaws, so that the anchor may be applied to either flange of the rail base without any substantial change in the character of the grip effected.

In applying the anchor to a rail, the jaws 11-11^a are hooked over one edge of the rail base flange and the anchor is then driven in the direction of its length transversely of the rail to force the jaws 11-11^a and 12-12^a into tight frictional engagement with the top and bottom surfaces, respectively, of the rail base. In driving the anchor home, the short shoulder 17 will snap over the lower corner of the rail base at the opposite side of the rail to lock the anchor in its applied position. The surface 25 adjacent the shoulder 17 will bear against the bottom surface of the rail base.

The modified anchor shown in Figs. 6 and 7 is made from a blank substantially the same as that shown in Fig. 4, except that the punching operations are so carried out that the sharp edges 27 and 28 are positioned at the inner faces of the U-shaped jaw portion 29. In this form of anchor, the bend 23^a, instead of being sharp, as shown in Figs. 1 to 3, is formed with a radius. This form of bend will permit sufficient flexing at the bend to allow for slight elongation of the body portion, that is to say, the body 10^a may be forced in the direction of its length to vary the distance between the shoulder 17^a and the vertical edges 31-32 of jaws at the opposite end of the anchor. When the anchor is applied, the distortion at the bend 23^a exerts a resilient force transversely of the rail to hold the rail-gripping jaws in their tight frictional grip on the base flange.

In the modifications shown in Figs. 8 and 9, the jaw end of the blank is bent to bear against one side face of the body and the end portion bent in a direction opposite to that of the previous forms described, so that the extremity of the jaw end bears flat against the forward side face of the jaw portion. The sharp edges 33 and 34 of the jaws are, in this form of anchor, positioned adjacent the outer faces of the jaw portion.

In the modifications shown in Figs. 10 to 12 inclusive, one edge of the blank is formed with a recess 35 of sufficient length to embrace the entire rail base. The recess 35 forms small shoulders 36 and 37, which engage opposite vertical edges of the rail base when the anchor is in its applied position. The bend 23^b of this form of anchor is made along a line extending at an angle of substantially 45° with respect to the longitudinal edges of the blank. By bending the end 21^b in this manner, the body portion 10^b, instead of extending at an angle to the bottom surface of the rail base, as indicated

in the previous figures, bears against said bottom surface throughout the entire width of the base. In other respects this form of anchor may be and preferably is the same 5 as that shown in Figs. 1, 2 and 3.

In Fig. 13 is shown a cross section of an anchor device taken on line 3—3 of Fig. 1, but showing the bend 23° of such radius that a slight clearance is provided between 10 the cross bar 10° of the anchor and the vertical portions 21° of the jaw portion. The radius of the bend 23° is preferably such as to provide rigidity between the jaw portion of the anchor and the cross bar and 15 at the same time provide greater clearance between the bar 10° and the jaw portion of the anchor than is shown between corresponding members of the anchors illustrated in Figs. 1, 2, 3, 5 and 8 to 11 inclusive. It 20 will be understood, however, that the construction shown in any of the figures above mentioned may, if desired, be formed in accordance with the showing of Fig. 13. The end portion 13° is also preferably so 25 disposed with relation to the bar 10° as to provide a slight clearance between the bar and the said end portion of the jaw end of the anchor.

The several embodiments illustrated in the 30 accompanying drawings will obviously suggest other modifications in structure that might be made without departure from the spirit of the invention. It will be understood, therefore, that I contemplate all 35 such changes in structure as come within the scope of the appended claims.

I claim:

1. A rail anchor made from a flat metal 40 strip of substantially uniform width formed along one margin with a rail base receiving recess and bent upon itself to provide a jaw portion adapted to be driven into gripping engagement with the rail base flange at one 45 side of the rail and formed with means for engagement with the base flange at the other side of the rail to lock the jaw portion of the anchor in its gripping position on the rail.

2. A rail anchor made from a flat strip 50 of substantially uniform width formed along one margin with a rail base receiving recess and bent along a line extending diagonally across said strip to provide a jaw portion which normally stands edgewise with respect to the rail base and adapted to be driven into gripping engagement with the rail base at one side of the rail and formed 55 with means for engagement with the base flange at the other side of the rail to lock the jaw portion of the anchor in its rail gripping position.

3. A rail anchor made from a flat metal 60 strip of substantially uniform width formed along one longitudinal margin with a rail base receiving recess and bent upon itself

to provide a jaw portion which normally stands edgewise with respect to the rail base and adapted to be driven into gripping engagement with said rail base flange, and formed along its other longitudinal margin 70 with a recess providing a shoulder for engagement with the rail base at the other side of the rail to lock the jaw portion of the anchor in its rail-gripping position.

4. A rail anchor made from a flat metal 75 strip of substantially uniform width formed along one marginal edge with a rail base receiving recess and bent upon itself along a line extending diagonally across said strip to provide a jaw portion adapted to be 80 driven into gripping engagement with the rail base at one side of the rail and formed along its other longitudinal margin with a recess providing a shoulder for engagement with the base flange at the other side of the rail to lock the jaw portion of the anchor 85 in its rail-gripping position.

5. A rail anchor made from a flat metal 90 strip of substantially uniform width recessed along one of its longitudinal edges and bent upon itself to provide a jaw portion of greater transverse width than the thickness of the blank and which normally stands edgewise with respect to the rail 95 base and adapted to be driven into gripping engagement with the rail base flange at one side of the rail and formed along its other longitudinal margin with a recess providing a shoulder for engagement with the base flange at the other side of the rail to lock 100 the said jaw portion in its rail gripping position.

6. A rail anchor made from a flat metal 105 blank of substantially uniform width recessed along one of its longitudinal edges and bent upon itself to provide spaced jaw portions adapted to be driven into gripping engagement with the rail base flange at one 110 side of the rail, and recessed along its other longitudinal margin to provide a shoulder for engagement with the other edge of the rail base to lock the jaw portions in their rail-gripping positions.

7. A rail anchor made from a flat metal 115 strip of substantially uniform width and bent to provide a jaw portion which stands at an acute angle with respect to the under-rail portion of the anchor and adapted to grip one flange of the rail and formed near the other end of the under-rail portion with a shoulder adapted to snap over the other edge of the rail base.

8. A rail anchor made from a flat metal 120 strip having an under-rail portion normally disposed edgewise with respect to the bottom face of the rail and having a portion recessed along one margin to provide a rail base gripping jaw and bent at an angle to the under-rail portion so as to normally stand 125 edgewise with respect to one base flange of 130

the rail; the said bend between the under-rail portion and said jaw portion of the anchor being sharp and the adjacent side faces of said portions being substantially parallel to each other.

9. A rail anchor made from a flat metal strip formed near one end with adjacent recesses, the walls of which taper toward one side of the blank, the end of the blank being bent at an angle to the under-rail portion so as to provide spaced rail-gripping jaws having sharp edges adjacent the outer faces of said jaws adapted to be compressed by contact with the top and bottom surfaces 10 of the rail base.

10. A rail anchor made from a flat metal strip having an under-rail portion normally disposed edgewise with respect to the bottom face of the rail and having a portion recessed 20 along one margin to provide a rail base gripping jaw and bent to a U-shaped configuration, and at an angle to the under-rail portion so as to normally stand edgewise with respect to one base flange of the rail; the said bend between the under-rail portion and the jaw of the anchor being sharp and the adjacent side faces of said portions being parallel with each other and the free end of said U-shaped jaw portion being pressed 25 substantially against the opposite face of said under-rail portion.

11. A rail anchor made from a flat metal strip having an under rail portion normally disposed edgewise with respect to the bottom 35 face of the rail when in its applied position and having a portion recessed along one margin and bent upon itself to provide a jaw portion of greater thickness than the blank and bent at an angle to the under-rail portion of the blank so that the jaw end thereof stands edgewise to the edge of the rail base, and means at the other end of the anchor for engaging the other edge of the rail base.

12. A rail anchor made from a flat metal strip having an under rail portion normally disposed edgewise with respect to the bottom face of the rail base and having a portion recessed along one margin and bent upon 45 itself to provide a jaw portion of greater thickness than the blank and bent at an acute angle to the under-rail portion of the blank to provide a relatively large tie-abutting surface and so that the jaw end of the

anchor will normally stand edgewise of the rail base, and means at the other end of the anchor for engaging the other edge of the rail base.

13. A rail anchor made from a flat metal strip having an under-rail portion normally disposed edgewise with respect to the bottom face of the rail and having a portion recessed along one margin to provide a rail base gripping jaw and bent at an angle to the under-rail portion so as to normally stand edgewise with respect to one base flange of the rail; the said bend between the under-rail portion and said jaw being so formed as to provide a slight clearance between the jaw portion and the under-rail portion of 65 the anchor.

14. A rail anchor comprising a substantially rigid jaw portion adapted to be driven into frictional gripping engagement with a base flange of a rail and formed with a gripping surface adapted to be compressed by contact with the rail to conform to the contour of the surface of the base flange 70 engaged.

15. A rail anchor comprising a portion 80 recessed to provide a jaw adapted to be driven into frictional gripping engagement with a base flange of a rail and formed with a gripping surface adapted to be crushed down by contact with the rail to accommodate rails having base flanges of greater thickness than the normal size of said recess.

16. A rail anchor comprising a substantially rigid jaw portion adapted to be driven into frictional gripping engagement with a base flange of a rail and formed with tapered surfaces providing sharp edges disposed in vertical alignment on opposite faces of said base flange and adapted to be compressed by contact with the rail to conform to the contour of the surfaces of the base flange 85 engaged.

17. A rail anchor comprising a substantially rigid rail gripping portion comprising spaced jaws adapted to be driven into frictional gripping engagement with a base flange of a rail and each jaw formed with a tapered surface providing a sharp edge adjacent the outer face of said jaw and adapted to be compressed by contact with the rail to conform to the contour of the surface of the rail flange engaged.

HAROLD G. WARR.
